UNITED STATES PATENT OFFICE.

HORACE L. CLARK, OF BEAVER DAM, WISCONSIN, ASSIGNOR OF ONE-FOURTH
TO AUGUSTUS ARMSTRONG, OF ALBERT LEA, MINNESOTA.

TABLET-COMPRESSING MACHINE.

SPECIFICATION forming part of Letters Patent No. 573,443, dated December 22, 1896.

Application filed July 3, 1896. Serial No. 597,989. (No model.)

To all whom it may concern:

Be it known that I, HORACE L. CLARK, of Beaver Dam, in the county of Dodge and State of Wisconsin, have invented certain new and useful Improvements in Tablet-Compressing Machines, of which the following is a full, clear, and exact description, reference being had to the accompanying drawings, forming a part of this specification, in which the corresponding letters of reference in the different figures indicate like parts.

My invention has for its object the accomplishment of the following purposes, viz: To so construct a tablet-compressing machine that the powder or material from which the tablet is formed may be automatically fed into a measuring device which may be so constructed and adjusted as to cause it to measure automatically any desired or predetermined quantity with accuracy and uniformity, thereby producing lozenges or tablets of unvarying size and weight.

A further object is to so construct the compressing mechanism as to enable it to be readily adjusted to conform to the requirements of the measuring device, and, finally, it is my purpose to so construct, arrange, and adjust the entire mechanism that it may be operated with certainty and accuracy while developing a speed beyond that of machines hitherto constructed for a like purpose.

To these ends my invention consists in the combination of elements hereinafter more particularly described, and definitely pointed out in the claims.

In the drawings, Figure 1 is a front elevation of my improved machine. Fig. 2 is a vertical sectional view of the same, taken upon the line 2 2, Fig. 1, viewed in the direction of the arrow there shown, the main shaft, upon which the driving-pulley is mounted, being broken off. Fig. 3 is a vertical sectional view taken upon the line 3 3, Fig. 1. Fig. 4 is a central longitudinal sectional view of said machine, a part of the same being broken off at the right. Fig. 5 is a vertical sectional view in detail of the feeding mechanism, and Fig. 6 is a rear view of said machine.

Referring to the drawings, *a* indicates the frame of the machine, which consists of a casting sufficiently heavy and strong to withstand

the strain and impact to which the machine is subjected at high speed. Supported in suitable bearings in the frame is the driving-shaft *b*, upon which is mounted a driving-pulley. 55 (Not shown in the drawings.) The middle portion of the shaft *b* is cut away, so as to form a crank or eccentric *c*, Figs. 2, 4, and 6, which is operatively connected with a sliding bar *d*, arranged to slide longitudinally in a suitable guide formed in the frame. The bar *d* is strongly constructed and is provided with an elongated recess *e* therein, Figs. 2 and 6, sufficiently wide to permit the eccentric *c* to rotate in the path indicated in the dotted 65 lines shown in Fig. 6, so as to enable the bar *d* to be reciprocated in a straight line. Within the recess *e* I place a loose block *f*, Figs. 4 and 6, the forward end of which is provided with a notched curve to fit the eccentric *c*, 70 while the rear end is rounded, as shown in Fig. 6, to fit loosely within a notch *f'*, formed in the bar *d*. It will thus be seen that the block *f* takes the place of an ordinary pitman, against which the eccentric bears to move the 75 bar *d* in one direction, while the opposite movement is accomplished by means of direct contact with the bar itself.

The movement of the bar *d* is intended, primarily, to accomplish the compression of the 80 tablet by means of a plunger *g*, Figs. 1, 3, 4, and 6, which is tapped into a lug *h*, Figs. 1 and 4, and secured from displacement by means of a jam-nut *i*. Mounted in suitable bearings in the frame is a horizontal shaft *j*, 85 having thereon a beveled gear *k*, adapted to be driven by means of a corresponding gear upon the main shaft *b*. A third shaft *l*, which I term the "feed-shaft," is arranged above and parallel with the shaft *j*, the two being 90 connected by means of a sprocket-chain *m*, Figs. 1 and 2, adapted to engage with sprocket-wheels mounted upon the shafts *j* *l*, respectively, as clearly shown.

The feed-shaft *l* is extended into a hopper 95 *n*, into which the powder is placed which is intended to be fed to the measuring-receptacle, and upon the inner end of the shaft is mounted a sector-shaped feed-wheel *o*, Figs. 3 and 5, which is provided with a series of 100 obliquely-arranged teeth *o'*, adapted to pass between similar stationary teeth *p*, located at

- the bottom of the hopper and extended upwardly and obliquely over a feed-opening g , formed in the bottom of the hopper. The feed-opening consists of an elongated slot of 5 uniform width formed in the top of a hollow cylinder r , into which is fitted a reciprocating plunger r' , mounted upon a rod r^2 , which passes loosely through a lug d' , extending from and rigidly attached to the bar d . A 10 nut r^3 is placed upon the outer end of the rod r^2 , between which and the lug d' is interposed a spiral spring r^4 , which tends normally to withdraw the plunger from the cylinder. An adjusting-nut r^5 is adapted to be engaged by 15 the lug d' , which serves to push the plunger into the cylinder in the manner and for the purpose hereinafter stated. A bar s , Figs. 1, 5, and 6, is pivoted, as shown, to the outside of the hopper, and the lower end is brought 20 into contact with the plunger r' , while a set-screw s' at the upper end enables the bar to be so adjusted as to limit the outward movement of the plunger. The purpose of this feature will be hereinafter explained. 25 Keyed or otherwise rigidly attached to a shaft t , Fig. 4, is a disk u , Figs. 1, 3, 4, and 5, having near its periphery and at equal distances from each other a series of cylindrical openings u' of a diameter adapted to receive 30 and fit the plungers r' and g , respectively. The main body of the disk u consists of a thin sheet of metal, while the openings are provided with cylindrical extensions u^2 , Figs. 1, 4, and 5, the inner ends of which abut 35 against the flat smooth face of a bracket or projection v , formed upon or attached to the frame. A space u^3 , as shown in said figures, is thus formed between the part v and the disk, of sufficient width to correspond to the 40 thickness of the thickest tablet which the machine is intended to form. Upon the inner end of the shaft t is keyed a disk t' , (shown in Fig. 4 and indicated in dotted lines in Fig. 3,) which is intended to form one member of 45 a rotary stop mechanism designed to give the disk u a quarter-revolution with each complete revolution of the shaft t , so that the cylindrical openings u' may be brought successively into registration with the plungers 50 r' and g , the former registration being indicated in Fig. 5 and the latter in Fig. 4.
- There are four reentrant curves t^2 formed, in the periphery of the disk t' at equal distances apart, the curve of each of which is 55 made to conform to the contour of the cylindrical hub j' upon the shaft j . In the face of the disk and intersecting each other at right angles are grooves t^3 , adapted to be engaged by a pin j^3 , mounted upon an arm j^2 , 60 projecting from the hub j' . A curved recess j^4 in the hub j' is adapted to receive the extended portions of the disk t' as the two are rotated. With each revolution of the shaft j the pin engages with one of the notches t^3 65 and moves the disk t' one-quarter of a revolution, when, one of the curved notches t^3 being in engagement with the hub j' , the disk

is thereby prevented from rotating either way and the openings u' are thereby brought into exact registration with the plungers r' g 70 and there retained during the operation of said plungers. This rotary stop mechanism permits of a positive action and enables the machine to be driven at a high rate of speed, while at the same time insuring accuracy of 75 registration.

In alignment with the plunger g and rigidly secured or formed within the frame is a hollow cylindrical die g' , Fig. 4, within which is permanently located a plunger w , having a body w' , extending back into close proximity to an adjustable stop x , Figs. 1 and 4. The stop is arranged obliquely to the axis of the frame, and upon the upper end is formed a rod x' , which is extended through the frame 85 and secured in position by means of an adjusting-nut, as shown. The lower end of the block x rests against a rigid shoulder a' , Figs. 1 and 4, projecting from the frame, which forms a solid abutment therefor, while the block x in turn serves as an abutment for the part w' . The raising or lowering of the block x by means of the nut at the top causes the latter to be brought closer to or removed farther from the rear end of the part w' , 95 thereby determining the possible longitudinal movement of the latter, the position of which when resting against the stop x determines the thickness of the tablets to be compressed. 100

The compression of the tablets is accomplished by forcing partially-compressed tablets into the die g' and against the end of the plunger w , which recedes until the part w' abuts against the stop x . An arm y , Figs. 1 and 4, the forward end of which is rounded, as shown, is rigidly attached to the main shaft a and when rotated is, with each revolution of the shaft, brought into engagement with a shoulder w^2 upon the part w' , which serves 110 to throw the plunger w forward with a quick stroke, thereby expelling the compressed tablet from the die.

Having thus described the various parts of my improved machine, I will now explain its 115 operation.

The hopper being supplied with powder, the set-screw s' is so adjusted as to limit the backward movement of the plunger r' through the action of the bar s , as shown in Fig. 5, so that 120 only the desired quantity of powder can be forced into the measuring receptacle or cylinder r . The movement of the feed-comb o is so timed that the powder is forced into the cylinder while the plunger is in the position 125 shown in said figure. The forward movement of the block d causes the lug d' to be brought into contact with the nut r^5 , thus forcing the plunger r' forward and compressing the powder into the cylinder u^2 and against 130 the face of the part v . The forward movement of the plunger is not sufficient to cause its end to be brought quite to the cylinder u^2 , and hence the movement of the disk u , which

occurs immediately upon the withdrawal of the plunger r' , shears off a portion of the partially-compressed tablet and leaves it in the end of the cylinder r adjacent to the cylinder u^2 until the next forward movement of the plunger occurs, when it is discharged, with the accumulated material, into the next cylinder u^2 , which is automatically presented. The tablet, which is partially compressed by the plunger r' into the cylinder u^2 , is carried forward by means of the rotary stop mechanism described a quarter of a revolution to a position in registration with the die in which is located the plunger w , when, by the forward movement of the plunger g , it is compressed with great force into the die and against the end of the plunger w , which is pushed back until the part w' is arrested by means of the abutment x . This action completes the formation and compression of the tablet. The disk u is then rotated after the withdrawal of the plunger g , when the arm y , striking suddenly in its rotation against the shoulder u^2 , forces the plunger w forward with a quick stroke, thereby causing the expulsion of the tablet from the die into the space u^3 between the disk and the face of the part v .

The thickness of the tablet is determined by the relative distance between the part w' and the face of the wedge-shaped block x . This distance may be adjusted with the utmost degree of fineness by means of the nut at the top of the screw-threaded portion x' . The relative weight of the tablets may be determined by the amount of the material fed with each revolution of the comb into the cylinder r , which amount may be controlled by means of an adjustable stop adapted to limit the backward movement of the plunger r' . The lever s and set-screw s' represent one means for accomplishing this result, which, it is obvious, may be secured in other ways.

Should it be desirable to produce a certain number of tablets to a given weight, such number may be weighed, and if found too heavy or too light the feed may be adjusted through the set-screw s' until the desired result is attained, which adjustment may be made without stopping the machine.

In view of the fact that my improved machine is positive in its action throughout, including that of the feed, I am enabled to run it at a much higher rate of speed than that of machines heretofore made without varying the weight or impairing the quality of the tablets formed therein.

Having thus described my invention, I claim—

1. A tablet-compressing machine in which are combined a hopper for the reception of the loose material, a measuring-receptacle in operative communication therewith, means for positively feeding the loose material to said measuring-receptacle, a reciprocating plunger adapted to partially compress and force said material out of said measuring-receptacle,

70 a suitable conveyer into which the material is forced, and a compressing-die to which the said partially-compressed material is transferred, substantially as described.

2. In a tablet-compressing machine, the combination of a hopper for the reception of the loose material, a measuring-receptacle in operative communication therewith, a feed mechanism for positively feeding the loose material to the measuring-receptacle at regular intervals, a reciprocating plunger adapted to partially compress and force said material out of said measuring-receptacle, a suitable 80 conveyer into which the material is forced, means for adjusting the longitudinal movement of said plunger whereby the quantity of material to be compressed with each movement may be predetermined and automatically measured, and a compressing-die to which the said partially-compressed material is transferred, substantially as described.

3. The combination in a tablet-compressing machine, of a hopper for the reception of the loose material, an adjustable measuring-receptacle, means for positively forcing said loose material into said measuring-receptacle at stated intervals, a rotary conveyer provided with a series of receptacles for receiving said tablets when partially compressed, a compressing-die into operative proximity to which the said partially-compressed material is conveyed, and means for actuating said rotary conveyer in harmony with the movement of said measuring device, substantially as described.

4. The combination in a tablet-compressing machine, of a hopper for holding the loose material, a measuring-receptacle in operative connection therewith, a rotary feed mechanism for positively feeding the loose material to said measuring-receptacle, means for automatically measuring the material therein, means for partially compressing the material into a tablet, a compressing-die, and means for removing the partially-compressed tablet thereto, substantially as described.

5. The combination in a tablet-compressing machine, of a hopper, a measuring-receptacle directly communicating with said hopper, an adjustable plunger for adjusting the measurement of the material, means for reciprocating said plunger at regular intervals, a rotary sector-shaped feeding device having a series of obliquely-arranged fingers upon its periphery, a series teeth in said hopper arranged to project obliquely over the opening communicating with the measuring-receptacle in a direction opposed to the direction of movement of said sector and arranged to contact with the teeth upon the latter, and means for causing the teeth of the sector to pass the opening only when the measuring-plunger is withdrawn, substantially as described.

6. The combination with a hopper and measuring-receptacle of a tablet-making machine, of the rotary sector-shaped feeding device located in the hopper, said device having a se-

ries of obliquely-projecting teeth upon its periphery a feed-opening forming communication between the hopper and measuring-receptacle, and a series of stationary teeth adjusted to coact with the teeth of the rotary feeding device and arranged to project obliquely over said feed-opening in an opposite direction from the course of movement of said device, whereby the material is directed and positively forced into the opening as a result of the opposite inclination of the opposing teeth, substantially as described.

7. In a tablet-making machine, the combination with a measuring-receptacle and means for forcing the material therein, of a reciprocating plunger for forcing the material out of the measuring-receptacle, a rotary disk having a series of openings in its face adapted to register with said measuring-receptacle, a rotary stop mechanism for actuating said disk in harmony with the movement of said plunger, a compressing-die, a compressing-plunger, a secondary plunger within the die, and means for thrusting the latter forward to expel the tablet after compression, substantially as described.

8. The combination in a tablet-machine, of a hopper, a measuring-receptacle in which to measure the tablet, a compressing-die, means for transferring the measured material to the compressing-die, a compressing-plunger adapted to force the partially-formed tablet into the compressing-die, a movable plunger within said die, an adjustable stop for limiting its backward movement to determine the

thickness of the tablet, and means for suddenly forcing said plunger forward after the withdrawal of said compressing-plunger, substantially as specified.

9. The combination in a tablet-compressing machine, of a stationary compressing-die, means for presenting the material thereto for compression, a reciprocating compressing-plunger, means for actuating the same, a movable plunger within said die, a stop for limiting its backward movement to gage the depth of the die, a lateral projection upon the body of said plunger, and a rotary arm adapted to engage with said projection after each backward movement of the compressing-die, substantially as described.

10. The combination in a tablet-compressing machine, of a main shaft and eccentric, a reciprocating bar adapted to be actuated thereby, a measuring-plunger and compressing-plunger respectively, in operative connection with said bar, a measuring-receptacle, means for feeding the material thereto, a compressing-die, and means for automatically transferring the material from the measuring-receptacle to said compressing-die, substantially as described.

In testimony whereof I have signed this specification, in the presence of two subscribing witnesses, this 17th day of April, 1896.

HORACE L. CLARK.
